MIXING AND THROTTLING VALVE FOR
GAS ENGINES

Joseph H. Jacobs, Minneapolis, Minn.

Application February 6, 1939, Serial No. 254,872

4 Claims. (Cl. 48—180)

My invention relates to mixing and throttling valves for internal combustion engines and particularly to a combination mixing and throttling valve for engines operated on gaseous fuel such as illuminating gas, natural gas or the like.

Where internal combustion engines are operated on gas received from a source of gas under pressure and mixed with air from the atmosphere, mixing and throttling means enabling operation of such engines under varying conditions of speed and load are usually likely to involve construction of a relatively intricate and expensive nature.

An object of my invention is to provide an efficient form of combined mixing and throttling valve particularly adapted for use with internal combustion engines driven by gaseous fuel.

Another object is to provide such a valve which is adjustable relative to the fuel and air ratio and wherein one adjustment affects the mixture throughout the entire range of throttle opening.

Still another object is to provide such a valve wherein a single shiftable member is employed for proportional throttling in unison of both the supply of gaseous fuel to the mixing chamber and the flow of mixture from the mixing chamber.

Yet another object is to provide such a valve wherein a single member is shifted in one direction for throttling action and in another direction for adjustment of the mixture.

A further object is to provide such a valve having a minimum number of movable and wearing parts and which is of particularly simple, compact, and inexpensive construction.

These and other objects and advantages of the invention will more fully appear from the following description made in connection with the accompanying drawing, wherein like reference characters refer to the same parts throughout the views, and, in which:

Fig. 1 is a side view of an internal combustion engine with an embodiment of my invention operatively associated therewith;

Fig. 2 is a vertical sectional view of an embodiment of my invention;

Fig. 3 is a sectional view taken along the line 3—3 of Fig. 2 as indicated by the arrows; and

Fig. 4 is a side view of the valve member of the device of Figs. 1, 2, and 3.

Referring to the drawing an embodiment of my invention is shown associated with a gaseous fuel burning internal combustion engine 5 having an intake manifold 5a and being served by a conduit 6 containing gaseous fuel such as nat-

ural gas, illuminating gas, or the like under pressure.

My mixing and throttle valve device in the embodiment illustrated includes a body 7 consisting in general of a horizontally extending substantially cylindrical portion 7a surmounted toward one end thereof by a vertical upwardly projecting substantially cylindrical portion 7b. The body 7 has a longitudinally extending bore 8 in the portion 7a thereof, the bore 8 being cylindrical in the portion thereof disposed below the upstanding part 7b of the body and being of increased diameter in the portion of the bore situated in the left-hand (as viewed in Fig. 2) part of the body portion 7a.

A rotary valve member 9 shown in Fig. 4 is placed in the cylindrical part of the bore 8 underlying the upstanding portion 7b of the body 7. The rotary valve member 9 is of hollow or tubular construction open at its left-hand end and having a closure or end wall 9a at its right-hand end. A shaft 10 is mounted on the end wall 9a in centrally located relation therewith so as to project outwardly thereof. The right-hand end of the bore 8 in the body 7 is provided with a closure plate 11 secured to the body 7 by suitable means such as screws 12. The plate 11 has in the center thereof an aperture wherein the shaft 10 is journalled. The lower portion of the valve member 9 is provided with a relatively narrow slot 13 extending circumferentially of the member 9 through an arc which is preferably in the neighborhood of 90°. The upper portion of the valve member 9 is provided with a rectangular opening 14 which constitutes a circumferentially extending slot having a width extending through the greater portion of the length of the valve member 9. The opening or slot 14 preferably extends through an arc in the neighborhood of 90°.

The lowermost portion of the body 7 has a slot 15 therein similar to the slot 13 in width and length of arc and situated in approximate alignment in a common plane with the slot 13, this plane being disposed normal to the rotational axis of the valve member 9.

The upstanding portion 7b of the body 7 contains a vertically extending interior space 16 extending from the upper end of the body portion 7b to the bore 8. The lower end of the interior space 16 is similar in dimension to the opening or slot 14 of the valve member 9 in a direction extending circumferentially from the member 9, and in a direction extending axially of the member 9 is somewhat smaller in dimension than the 55

slot or opening 14 of the member 9. The lower end of the interior space 16 in the body portion 1b is situated medially between the limits of the slot or opening 14 in a direction axially extending relative to the valve member 9.

The portions of the valve member 9 defining the slots 13 and 14 and the portions of the body 7 defining the slot 14 and the lower end of the interior space 16 cooperate to form two valves which open and close in unison and in proportion responsive to adjustive rotation of the valve member 9 relative to the body 7. For use in adjustively rotating the valve member 9 an operating arm 17 is mounted on the free end of the shaft 10 and is secured thereon in non-rotative relation therewith by means of a set screw 17a. The upper end portion of the arm 17 is provided with an aperture 17b for purposes of connecting a control rod or the like thereto. A helical compression spring 18 is placed on the shaft 10 between the closure plate 11 and the control arm 17 in encircling relation with the shaft 10 for the purpose of yieldably urging the valve member 9 to the right-hand limit of axial movement thereof in the bore 8 of the body 7. With the valve member 9 at its right-hand limit of movement the corresponding circumferentially extending sides of the slot 13 of the member 9 and the slot 15 of the body 7 are in alignment.

The mixing and throttle valve described above is so arranged that the left-hand open end of the bore 8 constitutes an air inlet opened to the atmosphere and communicating with the interior of the valve member 9. The slots 15 and 13 constitute a gaseous fuel inlet to the interior of the member 9 and the slot 14 and interior space 16 of the body 7 constitute a duct for leading the mixture of gaseous fuel and air to the manifold 5a of an engine. It will be seen that the degree of valve opening for admission of gaseous fuel will always be in proportion to the degree of valve opening for passage of mixture from the device to an engine as the valve member 9 is rotated to vary the fuel inlet and mixture outlet valves in unison. Thus regardless of the degree of throttle opening a certain ratio between fuel and air will be maintained within reasonable limits.

Means is provided in my device for adjustively varying the ratio of fuel and air. A bracket 19 is formed on the closure plate 11 and includes a free end portion 19a projecting upwardly past the free end of the shaft 10. The free end portion 19a of the bracket 19 is apertured at the projected axis of the shaft 10 and is internally screw threaded. A screw 20 is screw threadedly mounted in the screw threaded aperture thus formed and is provided with a lock nut 21 mounted on the screw and adapted to be forceably tightened against the outer side of the bracket portion 19a to lock the screw 20 in any adjusted position thereof. As the screw 20 is screwed inwardly toward the body 7, it will engage the free end of the shaft 10 and further inward movement of the screw 20 will displace the valve member 9 to the left against the pressure of the spring 18, thus placing the slot 13 of the valve member 9 out of complete registration with the slot 15 of the body 7. It will be seen that adjustment of the screw 20 will alter the cross sectional area of the opening through which gaseous fuel is admitted without varying the cross sectional area of the opening through which the mixture of air and gaseous fuel is carried from the interior of the valve member 9. Obviously such changes in the opening mentioned will vary the ratio of

gaseous fuel and air in the mixture delivered from my device. However, as the degree of valve opening is varied by adjustive rotation of the valve member 9 substantially the same mixture ratio will be maintained for all degrees of throttle opening and merely the delivered volume of mixture will be affected.

The valve structure described above includes as shown and described a single valve member 9 which gives throttling action responsive to rotative adjustments of the position thereof and mixture adjustment responsive to adjustive movement thereof in an axial direction.

The body 7 is arranged for convenient connection of a corresponding opening therein to an intake manifold such as the intake manifold 5a of the engine 5 and a gaseous fuel supply conduit such as the conduit 6. The upper end of the upstanding portion 1b of the body 7 is provided with an attachment flange 22 having bolt 20 receiving apertures 22a provided therein in accordance with conventional practice. A sleeve 23 is inserted to a portion of its length in the upper end of the interior space 16 which is increased in diameter to accommodate the sleeve 23 as shown in Fig. 2. The lower portion of the body 7 in the vicinity of the gaseous fuel admission slot 15 is machined to provide a downwardly facing horizontally disposed flat surface 7c and is provided with vertically apertured and internally screw threaded lugs 24 for securing a suitable connection element to the bottom of the body 7 in sealed relation with the flat surface 7c. The flange 22 may, of course, be connected to the usual attachment flange customarily provided on intake manifolds, and the interior of the supply conduit 6 may be placed in communication with the slot 15 by any suitable connection means designed to fit the flattened and lug equipped lower portion of the body 7.

It is apparent that I have invented a novel, extremely simple, compact and inexpensive mixing valve for internal combustion engines adapted for mixing gaseous fuel with air in adjustive ratio and controlling the volume of such mixture delivered to an internal combustion engine.

It will, of course, be understood that various changes may be made in the form, details, arrangement and proportions of the various parts without departing from the scope of my invention.

What is claimed is:

1. A mixing and throttling valve for mixing gaseous fuel and air for delivery to an internal combustion engine and controlling the flow of mixture thereto comprising, a hollow cylindrical valve member open at one end thereof and the interior of which constitutes a mixing chamber, and a casing having a cylindrical bore therein wherein said member is contained in rotatable and longitudinally slidable relation therewith, said casing having an opening to the exterior thereof in communication with the open end of said member to serve as an air inlet thereinto, said member having circumferentially extending slots therein diametrically opposite each other and of respective relatively small and large widths, said casing having therein diametrically oppositely situated ports substantially similar in dimensions to the respective ones of said slots and substantially aligned therewith axially of said member whereby, when said small and large ports are respectively connected to a source of gaseous fuel and the intake manifold of an internal combustion engine, said member may be adjustively rotated between positions thereof where-

in said slots are respectively aligned and totally out of registration with the ports of respectively corresponding dimensions for throttle action, and said member may be adjustively shifted axially between respective positions thereof wherein said narrow slot is respectively axially aligned with and completely out of axial alignment with said narrow port to effect mixture adjustment.

2. A mixing and throttling valve for mixing gaseous fuel and air for delivery to an internal combustion engine and controlling the flow of mixture thereto comprising, a hollow cylindrical valve member open at one end thereof, a casing having therein a cylindrical bore therein wherein said member is contained in rotatable and longitudinally slidable relation therewith, said casing having an opening to the exterior thereof adjoining and communicating with the open end of said member to admit air thereinto, an outwardly projecting shaft extending outwardly of the closed end of said member in co-axial relation therewith, said casing being apertured to accommodate said shaft in journalled relation therewith, said member having circumferentially extending slots therein diametrically opposite each other and of respective relatively small and large widths, said casing having therein diametrically oppositely situated ports substantially similar in dimensions to the respective ones of said slots and substantially aligned therewith mounted on said shaft for manipulation to rotate said member between positions thereof wherein said slots are respectively completely in and out of circumferential alignment with the respective correspondingly dimensioned ones of said ports, resilient means yieldably urging said shaft outwardly relative to said casing, and means for limiting outward projection of said shaft, said limiting means being adjustable for adjustive shifting of said member in an axial direction between positions wherein said narrow slot is respectively axially aligned with and completely out of axial alignment with said narrow port whereby, when said narrow and wide ports are respectively connected to a supply of gaseous fuel and the intake manifold of an internal combustion engine, throttle action may be had by rotating said shaft and mixture adjustment may be effected by adjustment of said limiting means.

3. A valve for mixing air and gaseous fuel and controlling delivery thereof to an internal combustion engine comprising, a casing having a cylindrical bore therein closed at one end and open to the atmosphere at the other end, said casing also having diametrically oppositely situated respective mixture outlet and gaseous fuel inlet

ports therein of respectively large and small dimensions axially of said bore, and a hollow valve member of cylindrical peripheral shape journalled in said bore and whose interior constitutes a mixing chamber for air and gaseous fuel, said valve member also having diametrically oppositely situated apertures therein generally similar to said respective parts in dimensions axially of said member and registerable with the respective ports of corresponding dimensions by suitably rotatively positioning said member whereby said member may be adjustively rotated to effect simultaneous throttle action on said ports, the end of said valve member adjoining the open end of said bore being open to constitute an air admission port of constant cross-sectional area.

4. A mixing and throttling valve for mixing gaseous fuel and air for delivery to an internal combustion engine and controlling the flow of mixture thereto comprising, a hollow cylindrical valve member open at one end thereof, a casing having therein a cylindrical bore therein wherein said member is contained in rotatable and longitudinally slidable relation therewith, said casing having an opening to the exterior thereof adjoining and communicating with the open end of said member to admit air thereinto, an outwardly projecting shaft extending outwardly of the closed end of said member in co-axial relation therewith, said casing being apertured to accommodate said shaft in journalled relation therewith, said member having circumferentially extending slots therein diametrically opposite each other and of respective relatively small and large widths, said casing having therein diametrically oppositely situated ports substantially similar in dimensions to the respective ones of said slots and substantially aligned therewith mounted on said shaft for manipulation to rotate said member between positions thereof wherein said slots are respectively completely in and out of circumferential alignment with the respective correspondingly dimensioned ones of said ports, an operating lever fixed on said shaft in outwardly spaced relation with said casing, a helical spring encircling said shaft between said lever and said casing and bearing at its respective ends against said lever and said casing, a bracket mounted on said casing and having a portion disposed outwardly of the free end of said shaft, and a screw disposed substantially axially of said shaft and screw-threadedly carried by said outwardly disposed portion of the bracket so that one end of said screw bears against the free end of said shaft.

JOSEPH H. JACOBS.
